METHOD OF ELECTROSTATIC ELECTRO-PHOTOGRAPHY

Louis Boydston Butterfield, Plainfield, N. J., assignor to Western Electric Company, Incorporated, New York, N. Y., a corporation of New York

Application May 19, 1950, Serial No. 163,007

6 Claims. (Cl. 95—1.9)

This invention relates to electrostatic electrophotography and more particularly to a method for reproducing images from an image bearing sheet of material.

Previous methods for reproducing images by use of electrostatic electrophotographic processes may be summarized broadly as processes wherein an invisible electrostatic image is formed on a surface of photoconductive material and then a visible powder is sprinkled on the photoconductive surface to develop a visible image from the latent electrostatic image. The next step is to transfer the visible powder image from the photoconductive surface to a sheet of paper and then to fix permanently the image to the paper by heat.

It is an object of this invention to provide a simplified method of electrostatic printing wherein the steps necessary to carry out the process are reduced.

It is an additional object of this invention to improve methods for economically reproducing designs, configurations or outlines of solid objects.

A further object of this invention is to provide a method for producing an electrostatically charged image on a sheet of insulating material in accordance with a light image projected onto the sheet of material.

Another object of the invention contemplates a method wherein an electrostatically charged image acts through a transparent or translucent sheet of material to attract powder to form a visible image.

A still further object of this invention is to provide a method for projecting a light image through a transparent or translucent sheet of material to form an electrostatic image on a photoconductive surface.

In accordance with one embodiment of the present method, a film having an image to be reproduced is placed in front of a light source. The image on the film is projected by a beam of light through an electrostatically charged transparent or translucent sheet of material onto a photoconductive layer whereupon the portions of the photoconductive layer subjected to the light are rendered conductive. Charges of opposite polarity to those on the transparent or translucent material now migrate, by attraction, through the lighted portions of the photoconductive layer to the under side of the transparent or translucent sheet of material to form electric couples which have negligible external fields. Thus the charges on the portions of the transparent or translucent sheet of material not subjected to light remain with an effective external field. The transparent or translucent sheet of material is then sprinkled with an electrostatically attractive visible powder to form a visible image of the electrostatic image. The sheet of material is then removed from contact with the photoconductive surface and finally the powder is fixed by any suitable process to the sheet of material to form a permanent visible image.

Other features and advantages of the invention will become apparent from the following detailed description taken in conjunction with the accompanying drawings in which:

Fig. 1 is a perspective view illustrating apparatus suitable for use in charging a photoconductive plate in accordance with the invention;

Figs. 2, 3 and 4 are views showing apparatus employing various methods of projecting an image through a sheet of material onto the photoconductive element;

Fig. 5 is a sectional view illustrating an arrangement of apparatus for applying powder onto an electrostatic image bearing sheet of material;

Fig. 6 is a perspective view showing the removal of a

2

sheet of material bearing a reproduced powdered image from the photoconductive plate;

Fig. 7 is a perspective view illustrating apparatus for permanently fixing a powdered image to the sheet of material;

Fig. 8 is a perspective view disclosing an alternative arrangement of elements suitable for use in electrostatically charging the photoconductive plate.

Referring to the drawing wherein like reference numerals designate the same elements throughout the several views, there is shown in Fig. 1 a metallic plate 10 having coated thereon a thin photoconductive layer 11. The metallic plate 10 may be made of copper, aluminum or any other suitable conductive or semi-conductive material which does not chemically react perniciously with the photoconductive layer 11.

Any one of a variety of photoconductive materials may be used for the layer 11 such as amorphous selenium, sulphur, germanium, lead sulphide, copper oxide, silver chloride, silver iodide and various combinations of selenium and sulphur. The term "photoconductive material" as used in this application includes those materials having such a change in their electrical characteristics in the transition from darkness to light that an electrostatic image can be produced and maintained by said materials during an electrostatic printing cycle.

A sheet of transparent or translucent electrically insulating material 12 is placed on top of the photoconductive layer 11. This sheet of material is made of any suitable electrically insulating material such as paper, cloth, or cellulose acetate, polystyrene or other plastics. It is upon this sheet of material that an image is to be reproduced.

A battery 13 or other suitable source of D. C. energy is connected by a wire 14 to the under side of the metallic plate 10. A corona discharge wire 15 is positioned above the sheet of material 12 and in close proximity thereto. This corona discharge wire is connected by a conductor 16 to the battery 13. It is preferable that the source of D. C. energy be suitable to maintain a potential of 5,000 to 10,000 volts between the corona discharge wire 15 and the metallic plate 10. Therefore, as the metallic plate 10, together with the selenium layer 11 and the sheet material 12 are reciprocated beneath the wire 15 a discharge takes place in the region between the corona discharge wire 15 and the sheet of insulating material 12. This particular procedure is carried out in a darkened space and as a result, the charges produced by the corona wire 15 are retained on the surface of the overlying sheet of insulating material 12.

Referring now to Fig. 2, a film 17 bearing an image to be reproduced is placed on top of the sheet of transparent or translucent material 12. The assembled film 17, transparent or translucent sheet of material 12, photoconductive layer 11 and metallic plate 10 are positioned with respect to a light source 18 arranged to uniformly illuminate the film 17. The light readily passes through those portions of the film 17 not having the image and through the sheet of transparent or translucent material 12 onto the photoconductive layer 11. Upon the light striking the photoconductive layer 11, the layer 11 is illuminated in the outline of the image to be reproduced. The portions of the photoconductive layer 11 subjected to the light are rendered more conductive thereby allowing electrostatic charges of opposite polarity with those on the surface of the sheet of insulating material 12 to migrate through the photoconductive layer 11 to the under side of the sheet of insulating material 12 to form electric couples with the charges on the outer surface. These electric couples will be formed over the entire area subjected to light and have a negligible external field.

An electrostatically charged image remains on those portions of the surface of the sheet of insulating material 12 which are not subjected to sufficient light to render conductive the underlying layer of photoconductive material 11. There is thus obtained on the transparent or translucent sheet of insulating material 12 an electrostatic latent image corresponding to the image contained on the film 17.

It is to be understood that original image bearing materials other than films may be used to produce the light image. Among the various types of originals that may be satisfactorily used to produce a light image are type-

written pages of transparent or translucent paper, drawings on tracing paper or cloth, designs contained on transparent or translucent sheets of plastic material, solid objects, the outline of which is desired to be reproduced, etc.

Fig. 3 illustrates another method of exposing the photoconductive layer 11 to a light source 20. The image bearing film 21 or other material containing a configuration to be reproduced is placed beneath the light source 20 and the image is projected through a lens 22 onto the transparent or translucent sheet of material 12. The light passes through the transparent or translucent sheet of material 12 to render the photoconductive layer 11 conductive in the outline of the image to be reproduced. The portions of the photoconductive layer 11, rendered conductive by the light, permit the migration of charges of opposite polarity to the under side of the sheet of insulating material 12 to neutralize the effect of the charges on the outer surface of the sheet of insulating material in the outline of the light image. Therefore, an electrostatically charged image with an effective external field remains on the surface of the sheet of insulating material 12. This charged image is a reproduction of the image on the film 21.

Fig. 4 illustrates an alternative method of projecting the image onto the photoconductive layer 11. A source of light 30 projects light onto an image bearing surface 31 to reflect the image through a lens 32 and through a sheet of transparent or translucent electrostatically charged insulating material 12 onto the photoconductive layer 11. The image bearing surface 31 in this instance need not be made of transparent or translucent material since opaque material serves to reflect adequately the light to produce the desired light image. The areas on the photoconductive layer 11 not sufficiently illuminated by light, corresponding to the image on the sheet 31, remain non-conductive. The remaining portions of the photoconductive layer 11 subjected to light are rendered conductive to permit the migration of charges to the under side of the sheet of insulating material 12. Inasmuch as these migrating charges are of opposite polarity with the charges on the outer surface of the sheet of insulating material 12, electric couples in the outline of the light image are formed which render non-effective the external field of the charges subjected to light leaving an effective electrostatically charged image in the outline of the image on the surface 31.

Upon exposure of the photoconductive layer 11 in any of the manners shown in Figs. 2, 3 and 4, an electrostatic latent image is produced on the transparent or translucent sheet of insulating material 12. This latent image may be made visible by sprinkling finely divided powder 35 over the surface of the transparent or translucent material 12 as illustrated in Fig. 5. This powder 35 may be of any type depending upon the type of finished print desired. Pulverized resins of many varieties may be used; however, resins which can be melted or made adhesive by heating are preferred. The powder 35 passing over the transparent or translucent material 12 is attracted to and adheres to the sheet of material 12 in the outline of the electrostatically charged image contained on the surface 12.

The sheet of transparent or translucent material 12 now bearing the powdered image, as shown in Fig. 6, is removed from the photoconductive layer 11 and heated by any of a number of arrangements, such as the radiant heater 40, illustrated in Fig. 7. The heat acts to fix permanently or set the powdered image 37 to the sheet of transparent or translucent material 12 by melting or rendering the powder adhesive so that it is retained on the sheet 12. Other means may be used to secure the powder on the sheet 12 such as by spraying the powdered image with a glue, lacquer or fluid adhesive compound.

In Fig. 8 there is illustrated an alternative method of charging the photoconductive layer 11. In this instance, the sheet of transparent or translucent material is not placed in contact with the photoconductive layer 11 during the charging operation by the corona discharge wire 15. The photoconductive layer 11 is charged by reciprocating the layer 11 and the metallic plate 10 beneath the corona discharge wire 15. This procedure is carried out in a darkened space in order that the photoconductive layer remains non-conductive to retain the charge on the surface of the photoconductive layer.

The next step in this alternative method is to place a sheet of transparent or translucent insulating material on the surface of the photoconductive layer 11. The film 17 is next placed on the sheet of transparent or translucent insulating material and then the assembled film 17, sheet of insulating material 12, together with the selenium coated metal plate 10 are subjected to a source of light as illustrated in Fig. 2. Upon the light striking the photoconductive layer 11, the lighted surface portions of the layer 11 are discharged through the now conductive portions of the photoconductive layer 11, through the conductive plate 10 and thence to ground 19. There remains on the outer surface of the photoconductive layer 11 an electrostatically charged latent image having a configuration identical with the image on the film 17.

The electrostatic latent image may also be produced on the photoconductive layer 11 by the methods disclosed relative to Figs. 3 and 4. The effective electrostatic field of the charged latent image acts through the sheet of transparent or translucent insulating material 20 to attract the electrostatically attractive powder to form a powdered image of the latent charged image. The visible image is then fixed on this sheet of insulating material by the method disclosed with regard to Fig. 7.

It is to be understood that the above-described methods and arrangements are simply illustrative of the application of the principles of the invention, and that many other modifications may be made without departing from the invention.

What is claimed is:

1. A method of electrostatic electrophotographic reproduction of images which comprises electrostatically charging the outer surface of a sheet of insulating material while its under surface is in contact with a photoconductive layer, producing an electrostatic image on said outer surface of said sheet by exposure to a light image, applying electrostatically attractive powder to the charged outer surface of said sheet, removing said sheet from said photoconductive layer, and then permanently affixing the powder to said sheet of insulating material.

2. A method of reproducing indicia on a sheet of light transmitting insulating material, which comprises producing an effective electrostatic field over the entire outer surface of a sheet of light transmitting insulating material, while the inner surface of said sheet is in contact with a layer of photoconductive material, projecting a light image of the indicia to be reproduced through said sheet onto said photoconductive layer to neutralize the portions of the electrostatic field subjected to light, applying electrostatically attractive powder to said outer surface of said sheet to develop a visible powdered image in the area of the remaining effective electrostatic field, separating said sheet from said layer, and thereafter fixing the powdered image to said outer surface of said sheet.

3. The method of making a reproduction of an image which comprises placing a sheet of light transmitting insulating material in contact with a photoconductive layer on an electrically conductive plate, advancing the material, photoconductive layer and electrically conductive plate through an electrostatic field to place an electrostatic charge on the outer surface of the light transmitting material, subjecting the image to be reproduced to a source of light to form a light image, projecting the light image through the light transmitting material onto the surface of the photoconductive layer to render the lighted portions of the photoconductive layer conductive to produce a charged image on the outer surface of the light transmitting material corresponding to the projected light image, dusting the outer surface of the light transmitting material with a finely divided electrostatically attractive powder to form a powdered image of the electrostatic image, removing said sheet from said photoconductive layer, and then permanently fixing the powder to the sheet of light transmitting material.

4. The method of reproducing a design from a sheet of material having a design thereon which comprises positioning a sheet of light transmitting insulating material in contact with a layer of photoconductive material, electrostatically charging the surface of the light transmitting material, reflecting light off the surface of the design bearing sheet of material to form a light image of the design, projecting the light image through the light transmitting insulating material onto the photoconductive layer to render the portions of the photoconduc-

tive layer subjected to light conductive to permit charges to migrate to the under side of the sheet of light transmitting insulating material to neutralize the charge on the outer surface of the light transmitting insulating material in the outline of the design, developing the portions of the photoconductive layer which remain charged by placing electrostatically attractable powder on the said charged portions of the sheet of light transmitting insulating material, separating the sheet of light transmitting insulating material from the photoconductive layer, and permanently fixing the powder to the sheet of light transmitting insulating material.

5. The method of electrostatic electrophotography wherein a sheet of material whose conductivity varies with illumination is placed with one side in contact with a sheet of inert conductive material, a sheet of translucent insulating material is placed in contact with the other side of the variable-conductance material, the outer surface of said translucent insulating material is electrostatically charged in the dark by exposing said insulating material to an electrical field produced by a potential of from approximately 5,000 volts to approximately 10,000 volts, an image whose configuration is desired to be reproduced is placed between a potential source of illumination and the three superimposed sheets, the source of illumination is energized to project light rays around the charged outer surface of the translucent insulating material, said light rays passing through the translucent material to the variable-conductance material, thereby increasing the conductivity of the variable-conductance material and causing the charge on the outer surface of the insulating material corresponding to the illuminated areas of the variable-conductance material to be rendered ineffective whereby an electrostatic latent image is formed on the outer surface of the translucent insulating material, applying electrostatically attractable powder to the outer surface of the sheet of translucent insulating mate-

rial to form a visible powder image thereon, separating the sheets of translucent insulating material and the variable-conductance material from each other, and then permanently fixing the powdered image to the sheet of translucent insulating material.

6. The method of electrostatic electrophotographic reproduction of images which comprises the steps of coating a metallic member with a photoconductive material, placing light transmitting insulating material on said coating of photoconductive material, subjecting the coated metallic member with said light transmitting insulating material thereon to an electrostatic field to place an electrostatic charge on the outer surface of said light transmitting insulating material, causing a light image of the image to be reproduced to be projected on the outer surface of said light transmitting insulating material and through the same to said photoconductive material, whereby the electrostatic charge on the light transmitting insulating material will be rendered non-effective in accordance with the light intensity of the light image on the photoconductive material, dusting the outer surface of said light transmitting insulating material with a finely divided electrostatically attractable powder, whereby powder will be attracted to the outer surface of said light transmitting insulating material in accordance with the effective electrostatic charge remaining thereon, removing said light transmitting insulating material from said coated metallic plate, and permanently fixing the powder to said light transmitting insulating material, whereby a reproduction of the image is obtained.
